UNITED STATES PATENT OFFICE.

BENJAMIN F. CALDWELL, OF WHEELING, WEST VIRGINIA.

STOVE-PIPE.

SPECIFICATION forming part of Letters Patent No. 361,861, dated April 26, 1887.

Application filed January 28, 1887. Serial No. 225,797. (No model.)

To all whom it may concern:

Be it known that I, BENJAMIN F. CALDWELL, a citizen of the United States, residing at Wheeling, in the county of Ohio and State 5 of West Virginia, have invented new and useful Improvements in Stove-Pipes, of which the following is a specification.

In the manufacture of stove-pipes it is very desirable to send out to the trade what are 10 known as partially-made stove-pipe sections, to be subsequently completed and connected by the dealer, or even by the purchaser, through the medium of flanged caps engaging longitudinal flanges on the pipe-sections. In 15 such stove-pipes it has been found difficult to complete and unite the sections so as to obtain certainty and accuracy of fit, and to have the seams in all the sections match when the stove-pipe is erected.

20 The objects of my invention are to improve such stove-pipes; to provide novel means for obtaining an accurate and certain fit between the adjoining ends of stove-pipe sections which have their edges connected by a flanged and 25 sliding cap; to provide a novel construction of parts, whereby a long horizontal or vertical stove-pipe can be erected without liability to sag, and whereby wire or other pipe-supports from the wall or ceiling are rendered unnecessary.

30 The objects of my invention I accomplish in the manner and by the means hereinafter described and claimed, reference being made to the accompanying drawings, in which—

35 Figure 1 is a perspective view of one of the stove-pipe sections having its edges connected by a cap and constructed according to my invention; Fig. 2, a broken perspective view showing portions of two sections of stove-pipe 40 united at their ends according to my invention; Fig. 3, a broken side elevation of portions of two stove-pipe sections united at their ends according to my invention; Fig. 4, a detail sectional view on the line *xx*, Fig. 2; Fig. 45 5, a similar view on the line *yy*, Fig. 3; Fig. 6, a longitudinal sectional view showing several pipe-sections united at their ends; Fig. 7, a longitudinal section through the connected end portions of two pipe-sections; Fig. 8, a perspective view of a pipe-section, showing the

joining-cap on the outside thereof; and Fig. 9, a detail view of one of the joining-caps.

In order to enable those skilled in the art to make and use my invention, I will now describe the same in detail, referring to the drawings, where—

The numeral 1 indicates a stove-pipe section having one end crimped, as at 2, to facilitate its insertion into another pipe-section. The pipe-section at each longitudinal edge is 60 turned inwardly to form flanges 3, which are connected by a joining-cap, 4, having longitudinal flanged edges 5, which can be slid along the flanges 3 and be engaged therewith to form the pipe-seam. In placing this joining-cap in 65 position one of its ends is left to project some distance beyond the end of the pipe-section, as shown at 6, so that these extending ends 6 alternately engage and clamp the flanges 3 of the pipe-sections, as in Fig. 6, so that all 70 the joining-caps break joints with the connected ends of the pipe-sections, thereby so strengthening them that long stove-pipes, either horizontal or vertical, can be erected without liability of sagging or displacement of the sections, so that pipe-supports of wire or other 75 devices from the wall or ceiling may be dispensed with.

To obtain an accurate fit between the ends of the stove-pipe sections, and to provide with 80 certainty that all the seams match, I construct the end of the pipe-section which is opposite the end where the joining-cap 5 is left projecting with tapering or wedge-shaped slot or opening 7, formed at the point where the pipe-seam terminates. (See Fig. 1.) The inner end of the joining-cap 5 terminates at the inner end of this tapering or wedge-shaped slot, so that one side of the latter is formed by one 85 of the flanges 3, and this side of the slot is 90 straight and in line with the pipe-seam.

In connecting the ends of two pipe-sections the slotted end of one section is forced into the end of the other section where the joining-cap projects, as at 6. This tapering slot 7 in the 95 end of the pipe-sections thus not only serves as a gage or guide to receive the flanges 3 of the pipe-sections, and thus place all the pipe in line, but when the pipe-sections are forced one into the other the edge of the wedge-shaped 100

slot acts as a wedge or clamp and forces the flanges 3 on the adjacent pipe-section more closely together, and thereby secures a tight fit between the parts, all of which will be evident by reference to Figs. 2, 3, and 7. The flanges 3 and joining-cap 5 are preferably placed on the interior of the pipe-section; but obviously they could be placed on the exterior of the pipe, as shown in Fig. 8. In either event, however, the pipe at the seam-line must be provided with the tapering slot 7 at the end of the pipe opposite to that where the joining-cap is permitted to extend, as at 6. The slot 7 thus acts as a gage or guide to insure a perfect and tight fit at the joined ends of the pipe.

By the described means of connecting the pipe-sections the manufacturer or wholesale dealer is enabled to ship large quantities of unjointed pipe-sections, one within another, with the caps detached and placed together in a package, ready to be connected when required.

Having thus described my invention, what I claim is—

1. A stove-pipe consisting of pipe-sections joined by sliding the end of one into the other, and each section having longitudinal edge flanges, and provided at one end with a tapering slot to embrace and press together the flanged edges of the adjacent pipe-section, and flanged caps for connecting the flanged edges of the cap-sections, substantially as described.

2. A stove-pipe consisting of a series of pipe-sections having longitudinally-flanged edges, and each connected by a flanged cap extending from the end thereof, said sections having their ends inserted, the one into the other, with the caps overlapping the joints, and each pipe-section having at one end a slot embracing and clamping the opposite flanged edges of the adjacent pipe-section, substantially as described.

In testimony whereof I affix my signature in presence of two witnesses.

BENJAMIN F. CALDWELL.
